UNITED STATES PATENT OFFICE.

NOEL L. ANTHONY, OF CRANSTON, RHODE ISLAND.

COIN-HOLDER.

1,032,319.

Specification of Letters Patent.

Patented July 9, 1912.

Application filed December 8, 1911. Serial No. 664,659.

To all whom it may concern:

Be it known that I, NOEL L. ANTHONY, a citizen of the United States, residing at Cranston, in the county of Providence and State of Rhode Island, have invented a new and useful Improvement in Coin-Holders, of which the following is a specification.

This invention pertains to certain new and useful improvements in coin holders, and has for its object to provide a coin holder which is in the form of a pocket-book having individual compartments for paper currency, halves, quarters, dimes, nickels and pennies and one in which the compartments are so formed that when the cover sections of the device are opened for the purpose of inserting or extracting a coin or coins, no danger of the coins dropping out of their respective compartments will exist.

20 A further object of the invention is to provide a simple and economical structure in which the parts can be made and assembled with minimum expense to thereby provide a device of this character which can be produced for the market with small cost.

In the drawings, Figure 1 is a perspective view of the device in completely opened position. Fig. 2 is a similar view of the same in closed position, and Fig. 3 is a section 30 taken on the line 3—3 of Fig. 2.

The device is formed to have a substantially rectangular base member 1 that has end extensions 2 the inner faces of which are padded as indicated at 3, the padding being secured to the extensions 2 in any approved manner. These extensions 2 provide end cover flaps which are folded inwardly and which meet at their inner ends when in closed position.

40 The base 1 carries a block 4 that may be formed of wood or any other suitable material and is secured to the base in any suitable way, the block 4 being formed with a series of compartments 5 of C-shape which 45 compartments have one side thereof extending through an end or side of the block, so that when a coin or coins are placed in the compartments an edge of the same will extend beyond an end or side of the block thus 50 providing a portion which can be grasped by the fingers to raise the coin up out of its compartment. As depicted in Fig. 1 of the drawings the compartments are made of varying diameters so that coins of different 55 values and denominations can be used, such

as halves, quarters, dimes, nickels and pennies.

Extending across the base 1 at right angles thereto is the cover proper which consists of a central portion 6 and extensions 60 7 7 which latter have clasp fastening means 8 8 of the head and socket type connected thereto to permit the extensions 7 7 to be connected in a manner depicted in Fig. 2 of the drawings. The padding 3 of the end 65 cover flaps 2 2 does not extend entirely throughout the area of same but terminates short of the inner end portions thereof, so that when the parts are in the position shown in Fig. 2 of the drawings the padding 3 will extend over the block 4 and thus be in position to engage with the coins that occupy the compartments 5. The central portion 6 of the cover proper is secured at its ends and one side thereof to the base member 75 1 so as to leave its opposite side open, thus forming a pocket 9 in conjunction with the base member 1, as shown in Figs. 1 and 3 of the drawings, which pocket can receive bills, 80 cards or other similar articles.

From the above it will be seen that the cover in reality has four flaps which extend from the opposite sides and ends of the block 1 and when folded to engage thereover securely retain the coins in the several compartments thereof. In addition a bill pocket is provided which is convenient to retain bills, cards and the like, and the same is effectively closed when the parts occupy the 85 position illustrated in Fig. 2 of the drawings. The coins of various denominations are thus securely held in separate compartments where they are readily accessible for purpose of removal, and a purse is presented which is exceedingly convenient and 90 which holds the coins against rattling in a 95 secure manner.

Having thus described my invention, I claim as new and secure by Letters Patent:—

1. A coin and bill purse consisting of a flexible base member having end extensions, a block secured to said base member between the extensions thereof and formed with a plurality of C-shaped openings which extend through the sides and end of the block to hold coins of various denominations, a cover proper having a central portion secured at one side and both of its ends to said base member and having its other side open 110

to form a bill or card receiving pocket in conjunction with the base member, said cover proper also having extensions provided with fastening means, and padding secured to the end extensions of the base member and adapted to engage on the top face of the block.

2. A coin and bill purse consisting of a flexible base member having end extensions, 10 a block having coin compartments secured to said base member between the extensions thereof, and a cover proper disposed at right angles to said base member having a central portion secured at one side and both 15 of its ends to said base member and having

its other side to open to form a bill pocket in conjunction with the base member, said cover proper having extensions which are adapted to overlie the extensions of the base member when the parts are in closed position, one of said extensions of the cover proper also extending over and closing the open side of said bill pocket.

In testimony whereof I have signed my name to this specification in the presence of 25 two subscribing witnesses.

NOEL L. ANTHONY.
